UNITED STATES PATENT OFFICE.

CHARLES A. SKERRY, OF WALTHAM, MASSACHUSETTS.

HYDROCARBON-BURNER.

SPECIFICATION forming part of Letters Patent No. 674,345, dated May 14, 1901.

Application filed April 7, 1899. Renewed October 12, 1900. Serial No. 32,972. (No model.)

To all whom it may concern.

Be it known that I, CHARLES A. SKERRY, of Waltham, in the county of Middlesex and State of Massachusetts, have invented certain new and useful Improvements in Hydrocarbon-Burners, of which the following is a specification.

This invention has relation to hydrocarbon-burners, and has for its object to provide certain improvements therein for effecting a perfect combustion of the fuel.

The invention therefore consists of a hydrocarbon-burner having certain features of construction and arrangement of parts, all as illustrated upon the accompanying drawings, described in the following specification, and set forth in the appended claims.

Referring to the said drawings, similar reference characters indicate similar parts or features wherever they occur.

Of the drawings, Figure 1 represents in horizontal section a burner constructed in accordance with my invention. Fig. 2 represents a vertical section on the line 2 2 of Fig. 1. Fig. 3 represents a different embodiment of the invention. Fig. 4 represents a section on the line 4 4 of Fig. 3.

The present invention while capable of many uses is particularly adapted for the boilers of automobile vehicles, such as set forth in my copending application filed concurrently herewith.

The fire-box comprises a casing 5, above which the boiler (not shown) is located. In the lower end of the casing is riveted or otherwise secured a ring 6, having a bead 7 and a flange 8, the bead projecting across the end of the casing. A disk or drum-head 9 is supported by the flange 8, its edges projecting into the U-shaped portion of the bead, and riveted to said disk is a concentric ring 10, to which a second disk or drum-head 11 is secured. The two heads, together with the ring 10, form a burner with a chamber for the reception of the gas, there being a tube 12 leading thereto from an aperture 13 in the side of the casing. A plurality of frusto-conical or upwardly-tapering open-ended tubes 14 are secured at their ends in the upper and lower walls 11 and 9 of said chamber and afford ducts for the passage of air through the chamber without communicating with the in-

terior thereof. The upper wall or disk 11 is provided with a plurality of small holes or apertures 15, surrounding the end of each tube 14, so that as the air passes up through the tubes it is commingled with the gas which escapes through the said apertures, and a perfect combustion results.

The gasoline or other fuel is stored in a tank or receptacle and is delivered under pressure to the pipe 16, which passes as a coil across the top of the burner beneath the boiler, where it is subjected to the heat of the flame, to the injector 17. The last-mentioned element is formed with a nozzle 18 and with a longitudinal duct 19, communicating with the aperture therein, to receive an automatically-operated valve 21. The flow of gas through the nozzle may be regulated by the hand-valve 20; but the automatic valve is controlled by the steam-pressure, whereby the flame is so regulated that the pressure in the boiler is maintained at a predetermined point.

The regulator for the automatic valve 19 consists of a slotted cylinder 22, connected at one end to the injector by a tube 23 and a coupling 24 and having its other end closed by a cylinder-head 25, into which a pipe 26 leads from the steam-boiler. A concavo-convex diaphragm 31 is placed inside the cylinder-head, and it is connected to the pin or valve 21, which passes through the end of the cylinder and the tube 23, there being a stuffing-box 27 inside the cylinder to prevent the escape of gas. A spring 28 bears against the diaphragm and against a cross-brace 29 in the cylinder to hold the valve in its open position, there being a stop 30 on the valve to limit its movement toward said open position.

To light the fire, a pan of alcohol is placed under the injector and ignited to convert the gasoline therein into gas. The escaping gas is then lighted above the burner in the combustion-chamber and the gasoline in the coil is quickly gasified, so that there is a steady flow to the nozzle. When the pressure of steam in the boiler rises beyond a predetermined point, the diaphragm is distended and forces the valve 21 against the pressure of spring 28 toward closed position to reduce the supply of gas until the steam-pressure is lowered.

It is evident that various changes may be

made in the apparatus which I have described without departing from my invention. For instance, in Figs. 3 and 4 I have illustrated another embodiment of the invention, in 5 which the burner is formed in sections 34, supported upon pairs of cross-bars 33, said sections being substantially sector-shaped or triangular in cross-section. Each section is formed in its upper surface with rows of apertures 36 to emit gas, and it is arranged in line with an inlet in the ring 10. The pipe 12 is formed with lateral branches 37, communicating with the inlets 35, and the gas as it leaves the nozzle passes into the gas-chambers and flows from the apertures into the combustion-chamber. Each casing 34 is provided with hangers 38 to take over the rods 33, as indicated in Fig. 4, and is readily removable. The air rises through the gas-chamber through the tapering slots or ducts between the sections and commingles with the gas, the apertures 36 being inclined, so that the streams of gas are deflected to cross the path of the currents of air. 15

20 In both burners there are a plurality of air and gas ducts interspersed across the plane surface thereof, whereby oxygen is supplied in sufficient quantities to cause a perfect combustion of the fuel.

25 It is to be understood that the term "gas" as used herein is not intended to specify a fixed gas, but a fuel in gaseous condition, due to the heat imparted to the gasoline or other liquid hydrocarbon as it passes through that portion of the pipe 16 above the burner. 30 While the term "vapor" might be applied to the fuel as it passes from the pipe 16, I have preferred to employ the term "gas," as hereinbefore used.

35 Having thus explained the nature of the invention and described a way of constructing

and using the same, though without attempting to set forth all of the forms in which it may be made or all of the modes of its use, I declare that what I claim is—

45

1. A burner of the character described comprising the casing 5, the ring 6 secured to the lower end thereof and having a flange 8, the disk 9 supported by said flange, the ring 10 rising from the disk 9 and concentric with 50 the casing, and a burner within the ring 10 and provided with a plurality of ducts for air and gas.

2. A burner of the character described comprising a combustion-chamber, and a burner 55 therein, said burner having inclined walls forming upwardly-flaring fuel-passages, the spaces between said walls forming upwardly-tapering air-passages, the upper and lower ends of the air-passages being open, and the 60 upper ends of the fuel-passages having perforations to cause the emission of fine jets of fuel close to the upper ends of the air-passages.

3. A burner of the character described comprising a combustion-chamber and a burner 65 therein, said burner being composed of the ring 10 and the upper and lower walls 11 and 9, the upwardly-tapering air-tubes 14 secured 70 to said walls and open at both ends, the upper wall 11 being provided with perforations surrounding and close to the upper ends of the tubes 14, and a connection with the space inside the ring and walls for supplying fuel to the upwardly-flaring spaces around said 75 air-tubes.

In testimony whereof I have affixed my signature in presence of two witnesses.

CHARLES A. SKERRY.
